Primary Examiner — Cynthia Ramirez*Assistant Examiner* — Xavier Marti-Santos(74) Attorney, Agent, or Firm — Sterne, Kessler, Goldstein & Fox P.L.L.C.CLAIM

The ornamental design for paint palette craft mat, as shown and described.

DESCRIPTION

FIG. 1 is a front perspective view of a paint palette craft mat in accordance with the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the figures show portions of the paint palette craft mat that form no part of the claimed design.
